PAINT SPRAYING MACHINE

Ivanhoe P. Denyssen, Lansdowne, Pa., and William E. Riecken, deceased, late of Leonia, N. J., by William E. Riecken, Jr., administrator, Leonia, N. J., assignors to Federal Telephone and Radio Corporation, New York, N. Y., a corporation of Delaware

Application February 19, 1945, Serial No. 578,736

14 Claims. (Cl. 91—45)

1

This invention relates to an apparatus or machine for spraying a coating of paint in a definite manner over metal strips having preformed operations thereon for the purpose of securing definite parts defined by said preformed operations for use in dry rectifiers.

Our invention is directed to the treatment of metal strips which have been previously operated on to define small discs which, after passing through our apparatus, are to be subsequently blanked out of the strip, the entire strip on the opposite side on which the discs are preformed being covered with a suitable rectifying material.

The discs are actually larger than necessary for mechanical reasons, and since the discs are to be used for instrument rectifiers and carry a very small current, we have found it very desirable to make the active surface on the discs a small proportion of the total area of the disc. This is desirable because of the fact that the larger the area of the disc, the greater the reverse current characteristic of the rectifier and this reverse-current characteristic should be kept as low as possible as compared with the forward-current characteristic. Also, it is desired that all of the discs have uniform characteristics, and consequently a uniform masking system for the actual contact areas of the rectifier discs is very desirable.

It is therefore the principal object of our invention to provide an apparatus for covering the strips carrying the rectifier discs with a suitable paint so that only a small central transverse area across the discs will be exposed for rectification purposes.

Another object of our invention is to provide a machine or apparatus which will do the covering or masking of the strip in an expeditious manner.

Another object of our invention is to provide an apparatus for attaining the principal object of the invention in a semi-automatic manner. These and other objects will appear from the specification which follows:

In general, the strips are of flexible material and are manually applied to the rim of a large rotatable wheel, being held thereto by suitable spring clips. As the wheel revolves, a masking tape from a feed roll is passed over rollers against the central portion of the strips, and the parts which act to hold the strips to the rim of the wheel are automatically covered by shields just prior to the application of a thin, rapid-

drying paint spray to the strips, which spray also passes over the masking tape.

After passing the spraying device, the shields are automatically moved back to normal position and the masking tape is withdrawn from its position of engagement with the strips, the strips passing on and being automatically released from their secured position for removal from the wheel. Our invention is depicted in 10 the following drawings, wherein:

Figure 1 is a plan view on a much reduced scale of the apparatus.

Figure 2 is a side view of Figure 1 on the line 2—2, certain parts of the frame being shown in 15 section.

Figure 3 is a side view of a small portion on an enlarged scale of certain of the parts shown in Figure 2.

Figure 4 is a section approximately on the line 20 4—4 of Figure 3, showing the means for holding the metal strip in position on the periphery of the wheel, and a portion of the shielding means in full lines in shielding position, being held there by an operating cam. The figure also shows the shielding means in dotted lines in non-shielding position.

Figure 5 is a view of the left-hand end of Figure 4 without the shield, showing the automatic means for separating the parts which lock the strip to the periphery of the wheel.

Figure 6 is a plan view of that part of the apparatus used for drawing the masking material through the machine.

Figure 7 is an enlarged view of a portion of 35 Figure 6, with certain parts removed.

Figure 8 is an enlarged, part-elevational and part-sectional view on the line 8—8 of Figure 7.

Figure 9 is a perspective view on an enlarged scale from the showing of Figure 2 of one of the 40 shielding members.

Figure 10 is a plan view of a section of the wheel rim showing one of the guard members of Figure 9 in guarding position.

Figure 11 is a plan view on a somewhat reduced scale of one of the strips carrying the current-rectifying material after it is passed through the machine depicted in the previous figures.

Referring now to the drawings, wherein like 50 numbers refer to corresponding parts, 1 is a framework which, as shown in Figure 2, is preferably made triangular in cross-section. The frame 1 carries bearing supports 2 and 3 for supporting a shaft 4 which is driven in any satisfactory manner as by a sprocket wheel 5 connected by a

chain 6 to a driving pinion 7 operated by a suitable source of power such as an electric motor 8.

On the outer end of the shaft 4, is mounted a wheel 9, this wheel 9 being mounted parallel with the hypotenuse of the triangular frame. Since the wheel has a diameter of between five and six feet, this method of mounting the wheel, as shown in Figure 2, saves considerable floor space. The wheel 9 has a rim 10 on which are arcuately mounted a plurality of engagement clips 11 and 12. Each of these clips is fastened in any suitable manner as by rivets 13 to a spring 14 fastened in any satisfactory manner as by screws or studs 15 to the rim 10.

The clips 12 have notches 16 therein to engage the edge of the metal strip 17 which has been preformed and which is to be further operated on by the present machine. The strip 17 is shown in Figure 11, and by way of illustration and not of limitation, is approximately eleven inches long and one-half inch wide, and one thirty-second inch thick, and is provided with two groups of partially punched discs 18, ten in number for each group. In addition, the strip is provided with holes 19, 20, 21 and 22, and notches 23 and 24. Furthermore, one side of the strip before it comes to the present machine has a side opposite the partially punched disc covered with a thin coating of rectifying material such as selenium.

Certain of the holes 19-22, although all may not be used, are for the purpose of engaging the ends of studs 25 which are adjustably positioned in the peripheral edge of the rim 10 whereby they may be adjusted so their projecting ends will just about come through the masking tape.

With this construction, an operator, positioned at the high side of the wheel 9, passes one of the strips 17 between the inside tapered surfaces of the clips 11 and 12 and over the ends of two of the spaced studs 25, which ends are adapted to engage the holes 19 and 22 at opposite ends of the strips, and one of the intermediate holes 20 or 21, it not being necessary to have a stud for both of these holes which, together with the other holes, are used for other purposes in connection with the strip after it leaves this particular machine. The location of the strips as they are mounted on the wheel is clearly shown in Figure 1.

Positioned adjacent the edge of the wheel, as shown in Figure 1, is a spraying apparatus composed of a receptacle or pot 26 which contains a suitable insulating, quick-drying paint or varnish that passes from the pot 26 downwardly through a tube 27 to a spray-nozzle portion 28. An air pipe 29, coming from a suitable source of compressed air, is brought to a chamber 30, from which it acts to force the paint in a fine spray against a longitudinal portion of a masking tape 31. It is to be understood that proper adjusting valves are provided for the paint and air pipes.

The masking tape 31 is a narrow paper tape carried on a freely rotatable reel or spool 32 mounted on the framework 1. As the tape 31 is drawn from the spool 32, it passes around a guide roller 33 and directly thereafter against the central longitudinal portions of the strips 17 in engagement with the rectifying material on the strips so that when the masking tape 31 leaves the peripheral edge of the wheel at the point 34, it leaves a narrow uncovered path 35 on the rectifying material.

As an alternative, the tape 31 may pass around a roller 36 carried on an arm 37 pivoted to the

frame at 38. Attached to the arm 37 is a cord 78 which passes over a roller 79 supported on suitable bearings in a frame member. After passing over the roller 79, the cord is attached to a suitable small weight 80 which, from Figure 1, will be noted is pulling in opposition to the tension of the masking tape 31. Consequently, if the tape 31 should break at some point away from the pulling or drawing structure 81, the arm 37 will be pulled by the weight 80 and the cord 78 so that the operating plunger 82 on the switch 83 is engaged by a boss 84 on the arm 37 and moves the contacts on the switch member 83 into open position, it being understood that the switch 83 is in closed position, thereby opening the circuit through the motor 8 and stopping the machine.

During the spraying operation, in order to keep the paint from covering up the strip attachment means—that is to say the clips 11 and 12 and studs 25—and rendering them inoperative in a very short time, we have provided a plurality of guard or shield means 39 which are pivoted to the rim 10 of the wheel, the pivot being formed by a pin going through rolled-over portions 40 formed on the members 39. Also, preferably formed integrally with the guard 39 at one end thereof, is a cover 41 having arms 42 and 43 projecting toward the pivotal portions 40. At the opposite end of the member 39, is a secondary cover 44 having inwardly projecting arms 45 and 46. The cover 41, with its arms, is adapted to cover two pairs of the closely associated clips 11 and 12, as well as the adjacent ends of two of the strips 17, as will be seen in Figure 10; while the cover 44 is adapted to shield the central section of the strip 17 embraced by the holes 20 and 21.

These shields or covers are carried into shielding position by the member 39 engaging a cam 47 carried on the frame 1 by support arms 48. It may be mentioned in passing that the cam 47 has an arcuate length of approximately seventy degrees, with an even rise of twenty-five degrees from the point 49 to the point 50, a twenty-degree dwell from the point 50 to the point 51, and a twenty-five-degree descent from the point 51 to the point 52. None of these angular spacings are at all critical and may be considerably varied.

The cam 47 is located about as indicated in Figure 2 so that the member 39 is moved to and held in shielding position a reasonable distance on either side of the spray-nozzle portion 28. Positioned in alignment with the spray-nozzle portion, above and below the rim and shields, are two exhaust pipes 53 and 54 to take away any excess spray or fumes from the paint.

After the strips have been carried around the wheel 9 nearly a full circumference, they are released through the medium of a roller 55 having oppositely disposed tapered surfaces 56 and 57 which pass between the tapered ends of the clips 11 and 12, spreading them apart and unlocking the approaching end of the strip 17 which, from its own resilience, will snap off the end of the guide pin 25 so that the operator may then take hold of the free end of the strip as indicated in Figure 1; and when the roller 55 engages the following pair of clips 11 and 12, the strip 17 may be removed, it being understood that at this particular time the paint has dried sufficiently so that the strip may be freely handled.

The masking tape 31, after leaving the rim of the wheel 9, passes around a roller 56 and additional rollers 57 and 58 mounted on the framework 1. After leaving the roller 58, the tape 31

moves into an auxiliary device 81 carried by the frame. The device 81 is shown more in detail in Figures 6, 7 and 8. This part of the apparatus is driven by a shaft 59 connected to the motor 8 through a suitable gear reduction. The outer end of the shaft 59 is supported by a pair of bushings 60 and 61 carried by frame members 62 and 63. An auxiliary shaft is carried by similar bushings at the opposite ends of the members 62 and 63, and between these two shafts is mounted, for rotation, a double-chain link belt composed of the parts 64 and 65.

Fastened to and carried by the double chain, are a plurality (only two being shown) of cross-pieces 66 which act as outboard guides moving on oppositely disposed ledges 67 carried by the members 62 and 63. Carried by each of the chains 64 and 65, are a plurality of arms 68 pivoted by studs 69 to portions 70 forming part of the members 66. The outer end of each of the arms 68 has an enlarged curved surface 71 adapted to engage a cam surface 72 on a plate 73. Operatively associated with each of the arms 68, is a member 74 having considerable resilience and which is adapted to be pushed by the arms 68 into gripping engagement with one side of the tape 31, the opposite side of the tape being simultaneously engaged with a similarly cooperative member on the opposite part 65 of the double chain.

As will be seen from Figure 6, there will be, for a short period of time, two of these sets of arms 68 and members 74 in simultaneous engagement with the tape 31, although there may be a period when the gripping members shown to the right in Figure 1 are moved out of engagement with the tape, leaving only one set of fingers in tape-gripping position.

After the arms 68 pass out of contact with the cam plate 73, they are moved by springs 75 into the position shown at the left in Figure 6, and the members 74 are released from gripping engagement with the tape 31, and this passes into a tube 76 which is connected to a compressed air pipe 77 that blows the tape out of the tube 76, thereby completing the travel of the masking tape through the apparatus.

It is to be understood that the speed of travel of the masking tape 31 through the auxiliary pulling device 81 is substantially synchronized with the speed of rotation of the rim 10 of the wheel 9. As a matter of fact, the tape adheres so closely to the strips 17 that are mounted on the rim of the wheel, that there is no slippage of the tape on the strips 17 being treated; yet the tension of the resilient members 74 is such that if there is a variation in the traveling speed of the tape-pulling belt, there may occur a slippage between the fingers 74 and the tape 31.

It will be readily appreciated from what has been said, that many of the mechanical details may be considerably varied without departing from the spirit of our invention or the scope of the appended claims.

What we claim is:

1. Apparatus for use in the process of making parts for electric-current rectifiers including, a supporting frame, a wheel rotatably mounted on the frame, means for rotating the wheel, strip holding means carried on the wheel for supporting on the peripheral edge of the wheel elongated flexible strips that have been previously operated on and covered along one side with current-rectifying material, with the rectifying material exposed, means for moving a mask over the rectifying material at the central longitudinal part

of each strip, means for spraying an insulating coating over the mask and portions of each strip, means for at least shielding said strip-holding means while they are passing the spraying means, means for removing the mask from the coated strips and further means for releasing the strips for removal from the wheel.

2. Apparatus for use in the process of making parts for electric-current rectifiers including, a supporting frame, a wheel rotatably mounted on the frame, means for rotating the wheel, strip holding means carried on the wheel for supporting, in end-to-end relation on the peripheral edge or rim of the wheel, elongated relatively narrow strips that have been previously operated on and covered along one side with current-rectifying material, with the rectifying material exposed, means for passing a narrow mask over the rectifying material at the central longitudinal part of the strips, shielding means including shields capable of being moved into a position overlying the strip holding means at the end junction of the strips and at a section intermediate the strip ends, means for automatically moving said shields into shielding position, means for spraying an insulating coating over the mask, the shields and all unshielded portions of each strip, said means for automatically moving said shields into shielding position serving also for automatically removing the shields from their shielding position, means for removing the mask from the coated strips and further means for releasing the strips for removal from the wheel.

3. Apparatus for use in the process of making parts for electric-current rectifiers as set forth in claim 2, further characterized in that the shielding means includes a plurality of devices pivotally mounted in arcuate relation along the rim of the wheel and having cover portions normally spaced away from the rim, with arms extending toward the rim which operatively engage with the shield moving means whereby the devices are moved successively into total shielding position as they approach the spraying means.

4. Apparatus for use in the process of making parts for electric-current rectifiers as set forth in claim 2, further characterized in that the mask is in the form of a tape drawn from a reel and passed into contact with the strips, while the shields are moved into shielding position directly after the tape is moved into contact with the strips, and then allowed to move into unshielded position directly after they pass the spraying means.

5. Apparatus for use in the process of making parts for electric-current rectifiers as set forth in claim 1, further characterized in that a motor is used to drive the apparatus and the mask is in the form of a narrow tape carried on a reel and passing over a roller carried on the free end of an arm pivoted to the frame, with means for holding the arm in a position so it will respond to said means, should the tape break, to move the arm into contact with a switch member to move said switch member sufficiently to open the switch and stop the motor, said switch being in the circuit of the motor.

6. Apparatus for use in the process of making parts for electric-current rectifiers as set forth in claim 1, further characterized in that a motor is used to drive the apparatus and the mask is in the form of a narrow tape carried on a reel and passing over a roller carried on the free end of an arm pivoted to the frame, a cord attached to the arm and passing over a roller and connected to a weight

serving, with the tape, to hold the arm in a neutral position but, should the tape break, acting to move the arm into contact with a switch interrupting the motor circuit and thereby stopping the apparatus.

7. Apparatus for use in the process of making parts for electric-current rectifiers as set forth in claim 1, further characterized in that said strip holding means comprises a plurality of pairs of clips resiliently mounted in arcuate relation on the rim of the wheel and having notches for slipping over the opposite edge at the ends of the said strips.

8. Apparatus for use in the process of making parts for electric-current rectifiers as set forth in claim 1, further characterized in that said strip holding means comprises a plurality of pairs of clips resiliently mounted in arcuate relation on the rim of the wheel and having notches for slipping over the opposite edge at the ends of the said strips, and further characterized in that adjustable positioning pins are located around the edge of the wheel rim to cooperate with holes in the strips for assisting in properly locating them on the wheel rim.

9. Apparatus for use in the process of making parts for electric-current rectifiers as set forth in claim 1, further characterized in that said moving means for the mask comprises an auxiliary device carried by the frame, said device having a power-driven belt, means carried by the belt to openly receive the mask at one end of the belt and to subsequently grip the mask to pull it along with the belt and finally eject the mask.

10. Apparatus for use in the process of making parts for electric-current rectifiers as set forth in claim 1, further characterized in that the mask is in the form of a narrow tape of suitable material and the moving means for the tape includes a power-driven belt having a plurality of spaced transverse guide members with cooperative transversely positioned arms pivotally mounted thereon, said arms carrying resilient members adapted to frictionally grip the tape on opposite sides thereof, and means for moving said arms to cause said resilient members to move into engagement with the tape and move it with the belt, and means for then releasing the tape near the end of the belt travel.

11. Apparatus for use in the process of making parts for electric-current rectifiers as set forth in claim 1, further characterized in that the mask is in the form of a narrow tape of suitable material and the moving means for the tape includes a power-driven double-chain link belt having a plurality of spaced transversely positioned guide members fastened to the two parts of the belt, a pair of cooperative arms pivotally mounted on each guide member, one on each part of the belt, and each having an associated cooperative resilient member for frictionally engaging the tape, spring

means for holding said arms and resilient members in tape-receptive position at the approach end of the belt, and cams for moving said arms and resilient members into pulling engagement with the tape and then releasing the arms at the end of the pulling travel of the belt, whereby said spring means will move the arms and resilient members to tape-receptive position and allow the tape to be ejected from the belt.

12. Apparatus for use in the process of making parts for electric-current rectifiers as set forth in claim 1, further characterized in that said moving means for the mask comprises an auxiliary device carried by the frame, said device having a power-driven belt, means carried by the belt to openly receive the mask at one end of the belt and to subsequently grip the mask to pull it along with the belt and finally eject the mask into a duct, with means for passing compressed air into the duct in a direction which will blow the mask material out of the duct.

13. Apparatus for use in the process of making parts for electric-current rectifiers including, a supporting frame, a wheel rotatably mounted on the frame, means mounted on the frame for rotating the wheel at a desired speed, a plurality of arcuately spaced cooperative means carried by and positioned on opposite sides of the rim of the wheel for engaging and holding elongated flexible strips that have been previously operated on and covered along one side with a current-rectifying material, with the rectifying material exposed, means for moving a suitable narrow paper tape over the rectifying material at the central longitudinal part of the strips, means carried by the wheel for shielding, for a relatively small arcuate movement of the wheel, said strip-holding means, means for spraying an insulating coating over the tape and all other unshielded portions of the strip while the shielding means is in shielding position, means for moving the tape from the wheel, and means for automatically releasing the strips from the holding means near the end of one revolution of the wheel.

14. Apparatus for use in the process of making parts for electric-current rectifiers as set forth in claim 13, further characterized in that the engaging and holding means for the strips are clips resiliently mounted on the wheel and having tapered ends projecting over the edge of the rim, while the releasing means comprises a small rotatable wheel mounted on the frame and shaped so as to pass between said tapered ends of the clips to spread them sufficiently to release the strips.
